CIGAR TIP

Robert F. Bulger, Levittown, and John Weller, Sr., Philadelphia, Pa., assignors to Bayuk Cigars Incorporated, Philadelphia, Pa., a corporation of Maryland

Filed May 22, 1967, Ser. No. 7,212

Term of patent 14 years

Int. Cl. D27—02

U.S. Cl. D85—8

FIG. 1.

FIG. 2.

FIG. 3.

FIG. 4.

FIG. 5.

FIG. 6.

FIG. 1 is a plan view of a cigar tip showing our new design,

FIG. 2 is an elevational view taken from the left side thereof,

FIG. 3 is a bottom plan view thereof,

FIG. 4 is an elevational view taken from the right side thereof,

FIG. 5 is an elevational view of the cigar engaging end thereof; and

FIG. 6 is an elevational view of the bit end thereof.

We claim:

The ornamental design for a cigar tip, as shown.
